UNITED STATES PATENT OFFICE.

CHARLES A. BOYER, OF WARSAW, INDIANA, ASSIGNOR TO HUGRO MANUFACTURING COMPANY, OF CHICAGO, ILLINOIS, A CORPORATION OF ILLINOIS.

DESIGN FOR A VACUUM-CLEANER CASING.

47,020.

Specification for Design.

Patented Mar. 2, 1915.

Application filed November 13, 1914. Serial No. 872,026. Term of patent 14 years.

To all whom it may concern:

Be it known that I, CHARLES A. BOYER, a citizen of the United States of America, residing at Warsaw, in the county of Kosciusko and State of Indiana, have invented a new, original, and ornamental Design for a Vacuum-Cleaner Casing, of which the following is a specification, reference being had to the accompanying drawings, forming part thereof.

Figure 1 is a view in perspective of a vacuum cleaner embodying my design; Fig. 2 is a view in side elevation thereof.

I claim:

The ornamental design for a vacuum cleaner casing, as shown.

CHARLES A. BOYER.

Witnesses:

C. EDWIN STAUB,

CARL E. KRATZSCH.
